UNITED STATES PATENT OFFICE.

HERMANN MENZEL, OF BERLIN, GERMANY, ASSIGNOR TO BERLIN-ANHALTISCHE MASCHINENBAU-AKTIEN-GESELLSCHAFT, OF BERLIN, GERMANY, A CORPORATION OF GERMANY.

RATCHET MECHANISM FOR REVERSIBLE APPARATUS FOR LIGHTING GAS FROM A DISTANCE.

1,109,350.

Specification of Letters Patent.

Patented Sept. 1, 1914.

Application filed June 19, 1913. Serial No. 774,717.

To all whom it may concern:

Be it known that I, HERMANN MENZEL, a subject of the German Emperor, and resident of Berlin, Germany, have invented 5 certain new and useful Improvements in Ratchet Mechanism for Reversible Apparatus for Lighting Gas from a Distance, of which the following is a specification.

This invention relates to ratchet mechanism 10 for reversible apparatus for lighting gas from a distance and has for its object to provide a mechanism such that the lighting apparatus, without its construction being changed, can be used both for ordinary 15 and inverted burners.

According to this invention the pawl engages the ratchet wheel in one position of the lighting device merely by gravity, while in the inverted position this engagement is brought about by the action of a tipping weight which, in the former position, does not act on the pawl. This arrangement insures the pawl engaging the ratchet wheel in both positions of the lighting 20 device with exactly the same force which was not the case in the ratchet mechanisms for gas lighting devices, hitherto known. For the adjustment of the lighting device by hand, as required in practical working, 25 there is provided a second pawl coöperating in the same manner with a tipping weight, whereby the ratchet wheel can be rotated as required by hand. This second pawl is further used as a locking pawl which prevents the ratchet wheel from turning back. 30

In the accompanying drawings which show one form of ratchet mechanism according to this invention in conjunction with apparatus for operating a gas burner actuated 40 from a distance by variations in the gas pressure, Figure 1 is a vertical section, partly in elevation, of a gas lighting device for upright burners. Fig. 2 is a side elevation thereof, the apparatus being reversed (turned upside down) for inverted gas 45 burners. Fig. 3 shows in section on line A—B of Fig. 1, the hand adjustment device, and Fig. 4 is a sectional plan on an enlarged scale, on the line C—D, Fig. 1, of 50 the pawl with the tipping weight.

In the apparatus shown in Fig. 1, the diaphragm 2 which closes at one side the casing 1, is exposed to the pressure of the

gas supplied by the pipe 3 and branch conduit 4 into the front chamber 5. The oscillation of the diaphragm 2 produced for instance by a pressure impulse is transmitted by the lever system 6, 7 connected to the diaphragm, to the feed lever 8 pivoted to the lever 7 and mounted loosely on a 55 spindle 28 supported in the casing 1. The feed lever 8 is provided with a lateral arm 10, which carries a stop pin 11 parallel to a spindle 9. Behind the feed lever 8, on the spindle 9 is pivotally mounted a tipping 60 weight 12 which, in the position of the ratchet mechanism shown in Fig. 1, rests on a stop pin 13 parallel to the spindle 9 and secured to the lighter arm 14 of a double-armed 65 pivoted pawl 14, 15 loosely mounted on the spindle 9. In the arrangement of the apparatus for upright burners, shown in Fig. 1, the engagement of the arm 15 of the pawl 14, 15, with the ratchet wheel 16, is therefore insured by the tipping weight 12 bearing 70 against the stop pin 13. The feed motion or advance of the wheel 16 is transmitted in the well known manner to the gas supply valve (not shown) in such a manner that the latter is temporarily opened or 75 closed, and in that way gas is admitted into the burner pipe or shut off from the same. If the apparatus above described is reversed, (that is to say, turned upside down) as 80 shown in Fig. 2 of the drawing, for employment with inverted gas burners, the arm 15 of the pawl 14, 15 will remain in engagement with the ratchet wheel 16 owing to the 85 action of gravity, while the tipping weight 12 bearing on the stop pin 11 of the arm 10, 90 will no longer exert any action on the pawl. By means of the ratchet mechanism above described, the gas lighting apparatus illustrated can therefore be used both for upright and inverted burners, without changing 95 its construction.

In the apparatus illustrated, the ratchet wheel 16 is also combined with a special hand adjustment device, shown more clearly in Fig. 3. The pawl 17, 18 of this adjustment 100 device also coöperates in the manner described, with a tipping weight 19. The arm 17 of the pawl is provided here with an arm 20 bent at right angles to engage the ratchet wheel 16 arranged laterally of the pawl. 105 The spindle 21 about which the pawl 17, 18

swings, is mounted on a feed lever 22 which is secured to the spindle 28 say by means of a square portion 23. To the end of the spindle 28 which projects through the casing 1, is secured a hand lever 24, by rotating which the spindle 28, and by means of the square portion 23, the feed lever 22, can be moved in such a manner that the pawl 17, 18 connected thereto, advances the ratchet wheel 16 to the desired extent. The feed lever 22 is controlled by a helical spring 25, and its movement is limited at both sides, by a double arm 26 mounted on the spindle 28 and striking an inclined projection 27 of the casing 1.

As will be seen, the pawl 17, 18 in the gas lighting apparatus illustrated is used not only as a feed pawl for the hand adjustment device, but also at the same time as a locking pawl preventing the wheel 16 from turning backward.

It will be understood that the ratchet mechanism above described is suitable for reversible gas lighting apparatus of all types more particularly also for those operated by electricity or compressed air.

I claim:

1. In ratchet mechanism for reversible apparatus for actuating gas burners from a distance, the combination of a ratchet wheel, a feed lever therefor, means for operating said lever, a pawl pivoted to said lever and engaging the ratchet wheel by gravity in one position of the apparatus and means co-operating with the pawl to insure its engagement with the ratchet wheel in the other position of the apparatus.

2. In ratchet mechanism for reversible apparatus for actuating gas burners from a distance, the combination of a ratchet wheel, a feed lever therefor, means for operating said lever, a pawl pivoted to said lever and engaging the ratchet wheel, means connected to the pawl adapted to retain it in contact with the ratchet wheel in one position of the apparatus and a stop for engaging said means when the apparatus is in the other position.

3. In reversible apparatus for actuating gas burners from a distance, the combination of a casing, a yielding pressure member therein, a gas supply pipe communicating with the casing, a ratchet wheel mounted within the casing, a feed lever for said ratchet wheel, a pivoted pawl mounted on said lever and engaging the ratchet wheel in one position of the apparatus, means connecting the feed lever and yielding pressure member and means co-operating with the pawl to insure its engagement with the ratchet wheel when the apparatus is in the other position.

4. In reversible apparatus for actuating gas burners from a distance, the combination of a casing, a yielding pressure mem-

ber therein, a gas supply pipe communicating with the casing, a ratchet wheel mounted within the casing, a feed lever for said ratchet wheel, a pivoted pawl mounted on said lever and engaging the ratchet wheel, means connecting the feed lever and yielding pressure member, means connected to the pawl adapted to retain it in contact with the ratchet wheel in one position of the apparatus and means for arresting said means when the apparatus is in the other position.

5. In reversible apparatus for actuating gas burners from a distance, the combination of a casing, a yielding pressure member therein, a gas supply pipe communicating with the casing, a ratchet wheel mounted within the casing, a feed lever for said ratchet wheel, a pivoted pawl mounted on said lever and engaging the ratchet wheel, means connecting the feed lever and yielding pressure member, a weight pivoted to the pawl adapted to retain the pawl in contact with the ratchet wheel in one position of the apparatus and means for supporting the weight in an inoperative position when the apparatus is in the other position.

6. In reversible apparatus for actuating gas burners from a distance, the combination of a casing, a yielding pressure member therein, a gas supply pipe communicating with the casing, a ratchet wheel mounted within the casing, a feed lever for said ratchet wheel, a pivoted pawl mounted on said lever and engaging the ratchet wheel, means connecting the feed lever and yielding pressure member, a weight pivoted to the pawl adapted to retain the pawl in contact with the ratchet wheel in one position of the apparatus, and an abutment adapted to support the weight in an inoperative position in the other position of the apparatus.

7. In ratchet mechanism for reversible apparatus for actuating gas burners from a distance, the combination of a ratchet wheel, a feed lever therefor, means for operating said lever, a pawl pivoted to said lever and engaging the ratchet wheel by gravity in one position of the apparatus, means co-operating with the pawl to insure its engagement with the ratchet wheel in the other position of the apparatus, a second pawl engaging the ratchet wheel by gravity in one position of the apparatus, means co-operating with said second pawl to insure its engagement with the ratchet wheel in the other position of the apparatus, a feed lever for said second pawl and means for actuating said feed lever.

8. In reversible apparatus for actuating gas burners from a distance, the combination of a casing, a yielding pressure member therein, a gas supply pipe communicating with the casing, a ratchet wheel mounted within the casing, a feed lever for said ratchet wheel, a pivoted pawl mounted on

said lever and engaging the ratchet wheel in one position of the apparatus, means connecting the feed lever and yielding pressure member, means coöperating with the pawl 5 to insure its engagement with the ratchet wheel when the apparatus is in the other position, a second feed lever mounted within the casing, means for actuating said feed lever from without the casing, a second pawl 10 pivoted on said second feed lever and engaging the ratchet wheel in one position of the apparatus and means coöperating with the second pawl to insure its engagement with the ratchet wheel when the apparatus is in 15 the other position.

9. In reversible apparatus for actuating gas burners from a distance, the combination of a casing, a yielding pressure member therein, a gas supply pipe communicating 20 with the casing, a ratchet wheel mounted within the casing, a feed lever for said ratchet wheel, a pivoted pawl mounted on said lever and engaging the ratchet wheel, means connecting the feed lever and yielding 25 pressure member, a weight pivoted to the pawl adapted to retain the pawl in contact with the ratchet wheel in one position of the apparatus, means for supporting the weight in an inoperative position when the 30 apparatus is in the other position, a second feed lever mounted within the casing, means for operating said feed lever from without the casing, a pawl mounted on said second feed lever and engaging the ratchet wheel, a weight pivoted to said second pawl adapted to retain it in contact with the ratchet wheel in one position of the apparatus, an abutment on the second feed 35 lever adapted to support the weight in an inoperative position in the other position of the apparatus, and stops on the second feed lever adapted to limit the movement thereof and enable the second pawl to act as a locking member for the ratchet wheel.

in an inoperative position when the apparatus is in the other position.

10. In reversible apparatus for actuating gas burners from a distance, the combination of a casing, a yielding pressure member therein, a gas supply pipe communicating with the casing, a ratchet wheel mounted within the casing, a feed lever for said ratchet wheel, a pivoted pawl mounted on said lever and engaging the ratchet wheel, means connecting the feed lever and yielding pressure member, a weight pivoted to the pawl adapted to retain the pawl in contact with the ratchet wheel in one position of the apparatus, an abutment on the feed lever adapted to support the weight in an inoperative position in the other position of the apparatus, a second feed lever mounted within the casing, means for operating said second feed lever from without the casing, a pawl pivoted to said second lever and engaging the ratchet wheel, a weight pivoted to the second pawl adapted to retain it in contact with the ratchet wheel in one position of the apparatus, an abutment on the second feed lever adapted to support the weight in an inoperative position in the other position of the apparatus, and stops on the second feed lever adapted to limit the movement thereof and enable the second pawl to act as a locking member for the ratchet wheel.

In testimony whereof I have signed this 70 specification in the presence of two subscribing witnesses.

HERMANN MENZEL.
